UNITED STATES PATENT OFFICE.

CHARLES S. BOCK, OF CHICAGO, ILLINOIS, ASSIGNOR TO ANDREW HOFFMAN MFG. CO., OF CHICAGO, ILLINOIS, A CORPORATION OF ILLINOIS.

CASEMENT WINDOW.

Application filed November 21, 1923. Serial No. 675,992.

To all whom it may concern:

Be it known that I, CHARLES S. BOCK, a citizen of the United States, residing at Chicago, in the county of Cook and State of Illinois, have invented certain new and useful Improvements in Casement Windows, of which the following is a specification.

The invention relates to casement windows, and is concerned particularly with that class of casement windows wherein the sashes are capable of both swinging and sliding movement in the frames.

One object of the invention is to provide, in a casement window of the character described, a light durable construction especially suitable for fabrication in metal.

Another object is to provide, in such a window, a thoroughly weather-proof arrangement requiring no auxiliary weather stripping under even the most adverse conditions of use.

Still another object is to provide, in such a window, a highly efficient manner of operation serving to effect a snug spring-pressed closure.

While the foregoing statements are indicative in a general way of the nature of the invention, other objects and advantages not herein specifically referred to will be appreciated upon a full comprehension of the novel features presented in the construction, arrangement and manner of operation of the casement window.

In order that the invention may be readily understood, one embodiment of the same is set forth in the accompanying drawings and in the following detailed description based thereon. Obviously the invention is susceptible of embodiment in other and varied constructional forms without departure from the essence of the invention or sacrifice of its material advantages; wherefore it is to be understood that the drawings and description are to be considered in an illustrative and not in any unnecessarily limiting sense.

In the drawings,

Fig. 1 is a front elevation of the casement window;

Fig. 2 is a horizontal section taken on the line 2—2 of Fig. 1;

Fig. 3 is also a horizontal section taken on the line 2—2 of Fig. 1, but illustrates the sashes in a partially open position;

Fig. 4 is also a horizontal section on the

line 2—2 of Fig. 1, but illustrates the sashes in another partially open position;

Fig. 5 is a vertical section taken on the line 5—5 of Fig. 1;

Fig. 6 is a horizontal section taken on the line 6—6 of Fig. 1;

Fig. 7 is a horizontal section taken on the line 7—7 of Fig. 1;

Fig. 8 is a perspective view of one of the upper mounting fixtures; and

Fig. 9 is a perspective view of one of the lower mounting fixtures.

The casement window illustrated in the drawings comprises a frame 10, two sashes 11 and 12 and means 13 for movably mounting the sashes in the frame.

The frame 10 includes a rectangular sheathing 14, an outwardly extending flange along the top, sides and bottom of the front periphery of the sheathing, an inwardly extending flange 16 along the sides of the front periphery of the sheathing, and an inwardly extending flange 17 along the top and sides of the rear periphery of the sheathing.

The two sashes 11 and 12 are hinged together at 18 in such a way as to permit arrangement of the same either in a coplanar position in the general plane of the frame or in an angular position of more or less degree in front of the frame. The sashes are provided, about the front peripheries of the same, with outwardly extending flanges 19 for contiguously overlapping the flanges 15 and 16 of the frame, and, about the rear peripheries of the same with unflanged edges 20 for perpendicularly abutting against the flanges 17 of the frame and a sill plate 21 just above the bottom of the frame. The portions of the flanges 19 along the hinged edges of the sashes approximately abut together, and one of the flange portions is provided with a lap strip 22; and the corresponding rearwardly disposed portions of the unflanged edges 20 are provided with flanges 23 which approximately abut together and are likewise spanned by a lap strip 24 provided on one of the flanges. The leaves of the hinges 18 are preferably secured to the flanges 23.

The construction and the interfitting relationship of the frame 10 and the two sashes 11 and 12 constitute a very desirable weather-proof association of the parts which is characterized by double front and rear con-

tacts between the parts and a continuous air chamber 25 about the parts in the channel way defined by the double front and rear contacts.

5 The means 13 for movably mounting the sashes in the frame comprises two upper fixtures 26, a co-acting guide 27 for the same along the top of the frame, two lower fixtures 28, and a co-acting guide 29 for the 10 same along the bottom of the frame.

The two upper fixtures 26 include flat horizontally disposed portions 30, pairs of supporting guide rollers 31 rotatably mounted on spaced spindles carried on the upper 15 surface of the portions 30, flat vertically disposed portions 32 extending downwardly from different ends of the portions 30, and lateral extensions 33 on the portions 32 for forming, in conjunction with the portions 20 32, resiliently flexible hinge leaves 34 for pivotal association with swinging hinge leaves 35 adapted for attachment to the upper portions of the otherwise unhinged sides of the sashes 11 and 12.

25 The guide 27 for the fixtures 26 comprises an inverted channel member which is fixedly positioned along the under surface of the top of the frame 10. The channel member has an inside width slightly greater than the diameters of the guide rollers 31, and is provided along its edges with inwardly turned flanges 36 for supporting engagement with the under surfaces of the guide rollers 31.

30 The two lower fixtures 28 are, in both construction and function, somewhat similar to the upper fixtures 26. The lower fixtures include flat horizontally disposed portions 37, sliding shoes 38 mounted for movement upwardly or downwardly in continued parallelism with the portions 37 on positioning studs 39, flat vertically disposed portions 40 extending upwardly from different ends of the portions 37, and lateral extensions 41 on the portions 40 for forming, in conjunction with the portions 40, resiliently flexible hinge leaves 42 for pivotal association with swinging hinge leaves 43 adapted for attachment to the lower portions of the sides of the sashes 11 and 12 at points directly below the fixtures 26.

35 The guide 29 for the fixtures 28 comprises an angle bar which is fixedly positioned along the upper surface of the bottom of the frame 10. One flange of the angle bar extends in a vertical plane and forms a narrow blade 44 for co-action with slots 45 in the sliding shoes 38 of the fixtures 28.

40 It will be understood, from the foregoing detailed description of the various parts of the casement window assembly, that when the centrally disposed hinged sides of the sashes are moved forwardly, the laterally disposed free sides of the same will approach each other in the general plane of the

frame, since the fixtures connecting the sashes with the frame are mounted for swinging movement relative to the sashes and for sliding movement relative to the frame.

45 The upper fixtures 26 and the lower fixtures 28 combine to permit of a weather-proof closure, since the front offsetting of the hinge pivots of the fixtures relative to the plane of engagement with the coacting 75 guides allows the flanges on the front of the sashes to overlap the front of the frame at all points of contact with the same.

50 In opening or closing the sashes, the hinges 18 connecting the sashes pass through the plane of the hinge pivots of the fixtures when the sashes are disposed at an angle of approximately ten degrees to the general plane of the frame, as shown in Fig. 3, because of the front offsetting of the hinge 80 pivots of the fixtures. The distance between the hinge pivots of the fixtures is accordingly less than the combined distances between each of the hinge pivots of the fixtures and the hinges 18 for all positions of the sashes 85 except that partially open position wherein the hinge pivots of the fixtures are resiliently sprung apart while the hinges 18 are temporarily in the plane of the hinge pivots.

90 The fixtures are so mounted on the sashes that they will reach the ends of their travel in opposite directions just before the hinges 18 on the sashes pass through the plane of the hinge pivots of the fixtures during the closing of the sashes. As a consequence, when the sashes are moved through this dead-center position, the hinge leaves 34 and 42 of the upper and lower fixtures are caused to flex resiliently whereby to spread the hinge pivots of the fixtures a sufficient 95 distance to permit the hinges 18 to pass into and through the plane of the hinge pivots of the fixtures, and, as soon as the sashes are past this dead-center position, the sashes will spring automatically into a tightly 100 closed position under the continuing tension of the hinge leaves. This feature of the invention insures a snugly closed position of the sashes when the sashes are moved into an approximately closed position and also 105 serves to maintain the sashes in the partially open position shown in Fig. 3 when such 110 position is desired, since the sashes, when moved into proximity to the dead-center position, tend to spring either forwardly into a more open position or rearwardly into the closed position—the direction of such tendency, of course, depending upon the position 115 of the sashes relative to the dead-center position.

120 The features of the invention which combine to produce the advantageous manner of operation above described are the hinged connection between the adjacent edges of the two sashes, the disposition of the hinge 125 130

5 pivots of the fixtures in a plane which is in front of the intermediate hinge pivot connecting the sashes when the sashes are in the closed position, the slight resilient flexibility of the portions supporting the hinge pivots of the fixtures, and an absence of any fixed abutments which would prohibit flexing of the portions supporting the hinge pivots in the most separated position of the fixtures.

10 The fixtures, it will be appreciated, do not require in their application specially constructed sashes, but are universal in that they may be attached without modification 15 to any of the sashes now in general use.

I claim:

1. In a casement window, a frame, two pivotally connected sashes abuttable laterally with portions of the frame upon being 20 swung into a common plane to close the opening in the frame, and a plurality of fixtures having portions associated with the frame for sliding movement of the fixtures in substantially fixed relation to a plane of 25 the frame and portions associated with the sashes for swinging movement of the sashes about pivotal axes on the fixtures, the said pivotal axes on the fixtures being separable under spring reaction during the closing of 30 the sashes to positions beyond those occupied by such axes when the sashes are closed, whereby to exert a pressure on the sashes when closed tending to maintain the same in closed position.

35 2. In a casement window, a frame, two pivotally connected sashes, having flanges about the front margins thereof which lap contiguously with portions of the vertical and horizontal members of the frame when 40 the sashes are closed to afford a weather proof closure, and a plurality of fixtures having portions associated with the frame for sliding movement of the fixtures in substantially fixed relation to a plane of the 45 frame and portions associated with the sashes for swinging movement of the sashes about pivotal axes on the fixtures which are located in a plane in front of the flanges of the sashes when the sashes are closed.

50 3. In a casement window, a frame, two pivotally connected sashes, and a plurality of fixtures having portions associated with the frame for sliding movement of the fixtures in substantially fixed relation to a plane of the frame and resiliently flexible 55 portions associated with the sashes for swinging movement of the sashes about pivotal axes on the fixtures.

4. In a casement window, a frame, two pivotally connected sashes, and a plurality of integral L-shaped fixtures having horizontally extending portions associated with the frame for sliding movement of the fixtures in substantially fixed relation to a plane of the frame and resiliently flexible 60 vertically extending portions associated with the sashes for swinging movement of the sashes about pivotal axes on the fixtures.

5. In a casement window, a frame having horizontally extending guide members adjacent its top and bottom, two pivotally connected sashes, and a plurality of integral L-shaped fixtures having horizontally extending portions in engagement with the 70 guide members of the frame for sliding movement of the fixtures in substantially fixed relation to a plane of the frame and resiliently flexible 75 vertically and laterally extending portions associated with the sashes for swinging movement of the sashes 80 about pivotal axes on the fixtures which are located in a plane offset from the location of the pivotal axis connecting the sashes when the sashes are closed.

6. In a casement window, a metal frame 85 having a flange about its front face, two pivotally connected metal sashes having outwardly extending flanges about their front faces adapted to overlap contiguously the flange of the frame when the sashes are 90 closed, and a plurality of fixtures having horizontally extending portions associated with the frame for sliding movement of the fixtures in substantially fixed relation to a plane of the frame and resiliently flexible 95 vertically extending portions associated with the sashes for swinging movement of the sashes about pivotal axes on the fixtures.

7. As an article of manufacture, a sash fixture having a horizontally extending portion adapted to slide along a guide member in substantially fixed relation to the member and a resiliently flexible portion adapted to pivot a swinging member.

8. As an article of manufacture, an integral L-shaped sash fixture having a horizontally extending portion, spaced bearing rollers carried by the horizontally extending portion for coaction with a guide member, a resiliently yieldable vertically extending portion at one end of the horizontally extending portion, and a hinge pivot along one side of the vertically extending portion.

In witness whereof I have hereunto signed my name.

CHARLES S. BOCK.
